UNITED STATES PATENT OFFICE

LEWIS A. JARVIS, OF GRAND RAPIDS, MICHIGAN

CAP FOR RADIATOR NECKS AND THE LIKE

Application filed May 24, 1928. Serial No. 280,152.

The main objects of this invention are:

First, to provide an improved cap for radiator necks and the like which may be quickly opened and closed and when closed provides an effective seal.

Second, to provide a structure having these advantages which is readily embodied in structures which lie flat or close to the radiator shell, the structure illustrated, however, being an adaptation to the projecting neck type of radiator.

Third, to provide a cap or closure of the type described which may be applied to or readily adapted to standard makes of motor vehicles.

Fourth, to provide a structure which is economical in its parts and assembly.

Objects pertaining to details and economies of construction and operation of my invention will appear from the description to follow. The invention is defined and pointed out in the claims.

A structure which is a preferred embodiment of my invention is illustrated in the accompanying drawings, forming a part of this application, in which:

Fig. 1 is a fragmentary view of a radiator cap embodying the features of my invention.

Fig. 2 is a fragmentary section on line 2—2 of Fig. 3.

Fig. 3 is a horizontal section on line 3—3 of Fig. 2.

Fig. 4 is a fragmentary perspective view showing certain of the parts in separated relation, these parts being enlarged to better show structural details thereof.

In the drawings similar reference characters refer to similar parts throughout the several views.

Referring to the drawings, 1 represents the externally threaded neck of a radiator which is provided with an inturned flange 2 forming a gasket seat. 3 indicates the shell of the radiator.

My improved cap or closure comprises a body member 4 internally threaded to engage the neck and being locked in position thereby by means of a set screw 5, this set screw having a head portion adapted to be broken off after the body member is positioned.

The body member is provided with a downwardly facing shoulder 6 clamping the gasket 7 arranged on the gasket seat 2. To effect a more perfect sealing, the face of the shoulder 6 has annular grooves 8 therein.

The body member is also provided with an upwardly facing annular channel 9 in which I arrange a gasket supporting ring 10 having a plurality of spaced fingers 11 whereby the gasket 12 is resiliently or yieldingly supported. The gasket itself is preferably of yielding material although thus yieldingly supported, it may be of fibre, and at the same time an effective seal is provided for the cover 13 which has an annular rib 14 coacting with the gasket.

The cover 13 is pivotally connected to the body member, the pintle 15 of the cover engaging a vertically elongated hole 16 in the pintle ear 17—see Fig. 2. This permits a limited vertical movement of the cover when closed and resting or supported by the cover gasket 12. A stop 18 is provided on the ear 17 to limit the opening swing of the cover.

The cover is locked in its closed position and clamped upon the cover gasket by means of the locking ring 19 rotatably mounted in the outwardly facing groove 20 of the body member, the locking ring having a plurality of inwardly projecting lugs 21 engaging in this groove. To permit engagement of these lugs with the groove, the lower wall of the groove has a series of slots 22 therein through which the lugs may be passed. After the ring is in position with these lugs in engagement, a stop pin 23 is inserted through the groove to coat with one of the lugs.

The body member is also provided with a plurality of recesses 24 adapted to receive the keepers 25 on the cover, these keepers having slots 27 therein adapted to align with the groove 20 so that the locking ring may be engaged and disengaged with the keepers by a rotative movement, thereby clamping the cover downwardly upon the gasket and locking it. The locking ring has inwardly facing slots 26 which may be aligned with the recesses 24. The pivot connection permitting the limited and vertical movement, allows for

adjustment of the cover so that it bears uniformly on the cover gasket.

The cover is quickly released or locked by a rotative movement of the locking ring, at the same time it is very secure as an effective joint or seal.

I have illustrated my improvements in an adaptation to a projecting type of radiator. However, it is well adapted for embodiment in the flat type. I have not attempted to illustrate such an adaptation herein as it is believed that this disclosure will enable those skilled in the art to embody or adapt my improvements as may be desired.

Having thus described my invention, what I claim as new and desire to secure by Letters Patent, is:

1. The combination of a body member, an upwardly facing annular gasket channel, a spring supported annular gasket supporting member arranged in said channel, a cover gasket supported by said gasket supporting member, a cover having an annular rib on its under side coacting with said cover gasket, a pivotal connection for cover to said body member permitting vertical movement with the cover when closed, a plurality of keepers on said cover, and a locking member on said body adapted to coact with all of said keepers.

2. In a structure of the class described, the combination of a body member having an annular groove therein, a cover pivotally mounted on said body member having limited vertical movement when the cover is closed, a spring supported gasket for said cover, a plurality of keepers on said cover and a locking member rotatably mounted on said body member coacting with all of said keepers.

3. In a structure of the class described, the combination of a body member provided with an upwardly facing gasket, a cover pivotally mounted on said body member for limited vertical movement when the cover is closed, a plurality of keepers on one of said members, a locking member rotatably mounted on the other member adapted to coact with said keepers, and a resilient element coacting with said gasket adapted to yield to permit the said vertical movement of the cover.

4. In a structure of the class described, the combination with a body member, of a cover pivotally mounted on said body member for limited vertical movement when the cover is closed, a plurality of keepers on one of said members, a locking member rotatably mounted on the other member adapted to coact with all of said keepers, and a sealing means interposed between said body and cover members yieldable to permit the sealing movement of said cover under the action of said locking member.

5. In a structure of the class described, the combination of a body member, a cover pivotally mounted on said body member for limited vertical movement when the cover is

closed, a plurality of keepers on one of said members, a locking member rotatably mounted on the other member coacting with all of said keepers, and a gasket means interposed between said cover and body members.

6. A radiator closure comprising an adapter having an opening therethrough, a cap permanently and hingedly connected to said adapter and means for temporarily locking said cap against hinged movement, said means including a projecting element on said cap having a groove therein, a second projecting element rotatably mounted relative to the adapter for extending into said groove and sockets formed in said adapter for each of said projecting elements.

7. A radiator closure comprising a base having a slot therein, a cap connected thereto having a projection thereon adapted to be received in said slot and a rim mounted on said base capable of limited rotary movement having means thereon for engaging said projection when in said slot for preventing the withdrawal thereof.

8. A tank closure comprising an adapter having an opening therethrough, a rim carried by said adapter and capable of limited rotary movement relative thereto, a cap hinged to said adapter and lugs carried by said rim and projecting into said adapter, said cap having lock projections extending into the adapter when the cap is closed, said lugs coacting with said lock projections to prevent their removal from such positions and thereby prevent hinged movement of said cap.

In witness whereof I have hereunto set my hand.

LEWIS A. JARVIS.
